UNITED STATES PATENT OFFICE.

BENJAMIN N. JONES, OF EAST ORANGE, NEW JERSEY.

AUTOMATIC CONTROL SYSTEM FOR ELEVATORS.

SPECIFICATION forming part of Letters Patent No. 726,307, dated April 28, 1902.

Application filed January 13, 1903. Serial No. 138,797. (No model.)

To all whom it may concern:

Be it known that I, BENJAMIN N. JONES, a citizen of the United States, residing in East Orange, county of Essex, State of New Jersey,

5 have invented certain new and useful Improvements in Automatic Control Systems for Elevators, of which the following is a specification, reference being had to the accompanying drawings.

10 This invention relates to electric systems of control for elevators, and particularly to the system of electric control set forth in Letters Patent of the United States granted to me February 25, 1902, and numbered 15 694,158. In said Letters Patent there is described a system in which there are main or motor circuits for furnishing power to drive a car, control-circuits which determine the direction and destination of the car, and operating-circuits in operative relation with the control-circuits and in which the push-buttons of the car and landings are located. A person desiring to use an elevator which is operated under the system described in the 20 25 aforesaid Letters Patent has but to press the landing push-button, which calls the car to that particular landing, get into the car, and press the proper car push-button to bring him to whatever landing he desires, the relation 30 between the operating and control circuits, the car push-buttons, and door-switches in that system being such that from the time he has opened the door at the landing of departure until he has closed the same and 35 from the time the car starts until the car has stopped at its destination there can be no outside interference with said car.

One object of this invention is to provide 40 means in connection with the foregoing system whereby there can be no outside interference with the car after it has stopped at its destination and before its passenger has alighted from the car and closed behind him the door of the landing.

45 Another object of this invention is to provide means in the operating or push-button circuit for opening said circuit immediately upon the closing of the control-circuit.

In the accompanying drawings, Figure 1 is 50 a view of a switchboard with certain parts of the apparatus embodying the present system of control secured thereon. Fig. 2 is a

diagram illustrating the several circuits of the present system and their relation to each other and to the parts shown on the switch-board.

55 The several parts of the system referred to herein—such as the relays, the locking device, the floor-limit switches, the resistance-regulating arm, &c.—are discussed in detail 60 and completely described in the above-mentioned Letters Patent, and for this reason when these parts are referred to in the present application it will be understood that they may be of the form and character shown 65 and described in the said Letters Patent. Moreover, inasmuch as the operation of the system of elevator control described in said Letters Patent is completely set forth therein it will be unnecessary in the present application to do more than trace the several 70 circuits of said system in so far as it may be necessary for a complete understanding of the present invention.

75 In the old system, as is fully described in the Letters Patent above referred to, the operating or push-button circuit is adapted to be opened by the movement of the resistance-regulating arm G. The movement of this arm, however, which movement is controlled 80 by accelerating-magnet G', will be somewhat sluggish at first, the elevator being under way some few seconds before said arm starts to move, and for this reason it is preferable to provide some means for opening the push- 85 button circuit immediately upon the closing of the control-circuit. Such means are furnished by providing contacts j and j² in the push-button circuit, which contacts are arranged in operative relation with a contact- 90 plate c³ on the core of the relay or locking-magnet C. In this way the movement of the core of relay C, which takes place immediately upon the closing of the control-circuit and which is substantially simultaneous with 95 the starting of the car, will open the operating or push-button circuit at the contacts j and j².

100 The operating or push-button circuits are adapted to be closed by their respective car push-buttons 1', 2', 3', and 4' and by their respective landing-buttons 1, 2, 3, and 4. Each of these circuits is arranged to pass through all of the door-switches S and one of the re-

lays a' , a^2 , a^3 , and a^4 . The current, therefore, through any one of the operating or push-button circuits will travel as follows: from the positive side of the main current-switch W to conductor 10, through the door-switches S, through the slack-cable stop S' , through the stop-button B, through a car push-button and one of the conductors y (in case the car is directed from within; otherwise through a landing push-button and one of the conductors y) to one of the relays a' , a^2 , a^3 or a^4 , to conductor 15, to contact j through contact-plate c^3 , to contact j^2 , to the negative side of the main current-switch W, to and through the source of current-supply, thus completing said circuit. The current through any of the operating or push-button circuits just described will energize its corresponding relay, whereby the core of said relay is actuated to close the control-circuit. The control-circuit which actuates a locking-magnet C, which magnet operates means for mechanically engaging and positively locking all of the operating-circuit relays in the inoperative position, save the one first actuated, is as follows: starting from the positive side of the main switch, through the wire 10, through the door-switches S, through the wire 11, through the emergency-stop B, through the wire 12, through the wire 13, to and through the coil of the locking-magnet C to one side of the controlling-switch V, through wire 17, through the contacts B', through one of the wires x , to one of the floor-limit switches u , through wire 31, to and through the coil of the directing-magnet D, through wire 30, through contact 29 across to contact 22 of the down circuit-breaker, through wire 37 to and through the coil of the circuit-breaker relay I, through wire 21, through contact j' , to and through the resistance-regulating-arm wire 16 to the negative side of the main switch, to and through the source of supply to the positive side of said switch, thus completing the circuit. As a result of this the locking-magnet will be energized, thus locking the core on relay 4 up in the operative position and the cores of all the other relays in the inoperative position. Directing-magnet D will be energized and its core being raised will close the main circuit.

The main or motor circuit through the reversing-switch and resistance-coil is as follows when the car is running up: from the positive side of the main switch by wire 30 to contact 32 on main upper-limit switch, to contact 34 on same switch by wire 35, to contact 36 on the up reversing-switch, to contact 37 when switch is closed, by wire 38 to contact 39, by wire 40 to terminal 41 on motor, to brushes 42 42, from brushes 43 43 to terminal 44, by wire 45 to contact 46, by wire 47 to contact 48, to contact 49 when switch is closed, by wire 50 to contact 51, by wire 52 to contact-plate 53 on resistance-regulator, by wire 54 to terminal 55 on motor, through series field-coils F' F² F³ F⁴ to terminal 56 on

motor, by wire 60 to one end of 57 of the resistance-coil, through the resistance-coil and contact-arm to terminal 58, by wire 59 to the negative side of main switch to and through the source of supply, thus completing the circuit.

The resistance-regulating arm G, adapted to be actuated by an accelerating-magnet G', is provided to gradually accelerate the speed of the car after said car has been set in motion by gradually cutting out the resistance in the main circuit, a latch being provided to retain said arm after all the resistance in said circuit has been cut out and releasing said arm when the car stops. Upon the movement of said resistance-regulating arm the control-circuit is broken at contact j' , but the current continues to flow in said circuit, because the core of the circuit-breaker relay I is raised and connection is made between the contacts m and m' , the control-circuit as established thereby being traced as follows: from the negative side of the main switch through the main wire 16, the pivot-pin on the resistance-regulating arm, the conductor x^3 , the contact x^4 , through contacts m and m' , thence through circuit-breaker coil I, thence to conductor 37, the remaining part of the control-circuit being the same as previously described.

It will be obvious that the breaking of the push-button or operating circuit at contacts j and j^2 will prevent any outside interference with the car after it is once in motion, even though the locking device should fail to work. When the car has reached its destined landing, the floor-limits will operate to break the control-circuit, which in turn operates to break the motor or main circuit, stop the car, and restore the system to its normal or initial condition. It will be noted, however, that inasmuch as the normal or initial condition of the system is established as soon as the car is brought to a stop the car might in the old system be at once set in motion by pressing any of the floor push-buttons, even before the occupant of the car has had time to open the landing-door, which breaks all the operating-circuits through door-switches S. In order to prevent such outside interference with the car after the car has come to a stop and before the occupant thereof opens the door of the landing where he is to alight, an auxiliary circuit is provided and will now be described. The primary object of such auxiliary circuit is to prevent the relays in the operating-circuit from becoming unlocked as soon as the control-circuit is broken, which occurs, as before explained, when the car comes to a stop. For this purpose the auxiliary circuit is made to pass through the coil of the locking-magnet C, whereby said magnet continues to be energized and the relays to be locked after the current in the control-circuit has ceased to flow and until the current through said auxiliary circuit is broken. Said auxiliary circuit is provided for by add-

ing to the system shown and described in Letters Patent No. 694,158, above referred to, a wire or conductor c , connecting the negative side of the main current-switch W with the 5 terminal or contact c' and by inserting a terminal or contact c^2 in conductor 20, connections being adapted to be made between said terminals by the contact-plate c^3 , provided upon the end of the core of the locking-magnet C . When said locking-magnet is energized, contact-plate c^3 is moved away from contacts j and j^2 to connect contacts c' and c^2 , whereby current will flow in the following 10 circuit: from the positive side of the main current-switch W to conductor 10, through the door-switches S , through conductor 11, stop-button B , and conductor 12, to and through the coil of magnet C to terminal c^2 , through contact-plate c^3 to conductor c to the 15 negative side of the main current-switch, thus completing the auxiliary circuit. If desired, lamps may be placed in said circuit on conductor c in order to indicate when the current is flowing through said circuit.

20 25 In the operation of the present system when the elevator comes to a stop current will continue to flow, notwithstanding the break in the control-circuit, through locking-magnet C , which is included in the auxiliary circuit, and said circuit can only be broken through stop-button B or through the door-switches S . Accordingly the occupant of the car still has the elevator under control after said elevator has come to a stop and may do one of 30 35 two things—either open the door of the landing at which the car has stopped, thus breaking the auxiliary circuit and unlocking the relays in the operating-circuit, or break the auxiliary circuit through stop-button B . In 40 the first case one of the switches S will be opened, and accordingly until the landing-door is again closed the car cannot be operated from any of the push-buttons, while in the second case the occupant still remains in 45 the car and having restored the system to its normal or initial condition through button B he may press any of the car push-buttons and send the car to another landing.

50 While the present invention has been described in connection with the system of electric control set forth in Letters Patent No. 604,158, it will be understood that said invention is not to be construed as limited in its application to that system alone.

55 I claim as my invention—

1. In a system of electric control for elevators, the combination of an operating-circuit, a control-circuit in operative relation therewith, means for furnishing power to drive a 60 car, means for making the control-circuit independent of the operating-circuit while a car is moving, and an auxiliary circuit adapted to be closed by the last-named means, and coöperating with said means to make the control-circuit independent of the operating-circuit 65 after the car has come to rest.

2. In a system of electric control for eleva-

tors, the combination of an operating-circuit, a control-circuit in operative relation therewith, means controlled by said control-circuit 70 for furnishing power to drive a car, means also controlled by said control-circuit for making that circuit independent of the operating-circuit while the car is moving, and an auxiliary circuit adapted to be closed by said last-named means and coöperating with said means to make the control-circuit independent of the operating-circuit after the car has come to rest.

3. In a system of electric control for elevators, the combination of an operating-circuit, relays arranged to be actuated by said operating-circuit, a control-circuit adapted to be closed by any of said relays, a second relay arranged to be actuated by said control-circuit and adapted while energized to lock the first-named relays, and an auxiliary circuit adapted to be closed by said second relay, said auxiliary circuit being arranged to pass through said second relay, whereby said relay continues to be energized after the control-circuit is opened and until the current in said auxiliary circuit is broken.

4. In a system of electric control for elevators, the combination with a car, means for supplying power to drive said car, and a stop-button in said car, of an operating-circuit, relays arranged to be actuated by said operating-circuit, a control-circuit adapted to be closed by any of said relays, a second relay arranged to be actuated by said control-circuit and adapted while energized to lock the first-named relays, and an auxiliary circuit adapted to be closed by said second relay, said auxiliary circuit being arranged to pass through said second relay, whereby said relay continues to be energized after the control-circuit is opened and until the current in said auxiliary circuit is broken at said stop-button.

5. In a system of electric control for elevators, the combination of a car, means for supplying power to drive said car, and door-switches at the several stations, of an operating-circuit, relays arranged to be actuated by said operating-circuit, a control-circuit adapted to be closed by any of said relays, a second relay arranged to be actuated by said control-circuit and adapted while energized to lock the first-named relays, and an auxiliary circuit adapted to be closed by said second relay, said auxiliary circuit being arranged to pass through said second relay, whereby said relay continues to be energized after the control-circuit is opened and until the current in said auxiliary circuit is broken at any of said door-switches.

6. In a system of electric control for elevators, the combination of an operating-circuit, relays arranged to be actuated by said operating-circuit, a control-circuit adapted to be closed by any of said relays, a second relay arranged to be actuated by said control-circuit and adapted while energized to lock the first-

named relays, floor-limits in said control-circuit by which said circuit is adapted to be opened, and an auxiliary circuit adapted to be closed by said second relay, said auxiliary 5 circuit being arranged to pass through said second relay whereby said second relay continues to be energized after the control-circuit is opened by any of said floor-limits and until the current in said auxiliary circuit is 10 broken.

7. In a system of electric control for elevators, the combination with a car, means for supplying power to drive said car, a stop-button in said car, and door-switches at the several 15 stations, of an operating-circuit, relays arranged to be actuated by said operating-circuit, a control-circuit adapted to be closed by any of said relays, a second relay arranged to be actuated by said control-circuit and 20 adapted while energized to lock the first-named relays, floor-limits in said control-circuit by which said circuit is adapted to be opened, an auxiliary circuit adapted to be closed by said second relay, said auxiliary 25 circuit being arranged to pass through said second relay, stop-button and door-switches whereby said second relay continues to be energized after the control-circuit is opened by any of said floor-limits, and until the current 30 in said auxiliary circuit is broken at said stop-button or at any of the door-switches.

8. In an electric-control system for elevators, the combination of operating and con-

trol circuits, a relay to close the control-circuit for each floor, a push-button for operating said relay, means for positively engaging and mechanically locking, in the inoperative position, all relays, save the one first actuated, and an auxiliary circuit adapted to be closed by said means and coöperating with the same 40 for the purpose specified.

9. In a control system for electric elevators, the combination of a control-circuit, an operating-circuit for closing the control-circuit, an auxiliary circuit, and a single relay in both 45 said control and auxiliary circuits adapted when energized to open the operating-circuit and to close said auxiliary circuit for the purpose specified.

10. In a control system for electric elevators, the combination of a control-circuit, an operating-circuit for closing the control-circuit, an auxiliary circuit, and a single relay in both 50 said control and auxiliary circuits, a contact-plate on the core of said relay, said 55 contact-plate being normally in the operating-circuit and adapted when said relay is energized to open said operating-circuit and to close said auxiliary circuit for the purpose specified.

This specification signed and witnessed this 7th day of December, 1902.

BENJAMIN N. JONES.
